UNITED STATES PATENT OFFICE.

THOMAS H. MATHIAS, OF BUFFALO, NEW YORK, ASSIGNOR TO LACKAWANNA STEEL COMPANY, OF LACKAWANNA, NEW YORK, A CORPORATION OF NEW YORK.

ROLL-GUIDE.

1,286,465.

Specification of Letters Patent. Patented Aug. 14, 1917.

Application filed October 26, 1912. Serial No. 727,848.

To all whom it may concern:

Be it known that I, THOMAS H. MATHIAS, a citizen of the United States, residing at Buffalo, in the county of Erie and State of New York, have invented new and useful Improvements in Roll-Guides, of which the following is a specification.

My invention relates to the rolling of steel sheet piling of the nature described in Patent No. 923,110 of May 25, 1909, and consists in a peculiarly formed and arranged guiding element to insure of the proper introduction of the piling to the rolls and in the final pass to coöperate with the rolls to insure of the true and uniform curvature of the flanges in the finished piling. The pile sections in question are of the so-called double interlock type and are provided with short thickened flanges or "thumbs" projecting on one side at each end of the web, and with long, tapering, curved flanges called "guards" or "fingers" projecting at each edge on the side opposite to the thumbs and curved outwardly beyond the short flanges to form, with the latter, grooves for interlocking along each edge of the section. To roll this section presents a peculiar problem and to a large degree the successful rolling depends upon the proper adjustment of the section when presented to the rolls.

My improved guiding element is adapted conveniently to permit of the required minute adjustments of the parts and their relative positions and rigidly to secure the parts in their adjusted positions in correct relation to the pass.

The drawing herewith illustrates my invention and the reference numerals of this description are applied to like parts in the different views. Figure 1 illustrates the guide-element or entry box of my invention in front elevation. Fig. 2 is a side elevation of the same and illustrates the bending over of the longer flange. Fig. 3 is a plan view of the entry guides with parts shown in section and Fig. 4 is a cross sectional view on line 4—4 of Fig. 3 the better to illustrate certain features.

In the figures the usual rolls of a rolling mill are indicated by *a* and *b* and are here shown comprising that portion of the rolls which form the finishing pass, as described in my Patent No. 1,176,308 of March 21, 1916, whereby the last step in forming the piling section referred to is accomplished.

As therein explained this step consists in the bending over of the longer or finger flange of the section so as to inclose the hook flange of an adjoining section. The piling section is shown sectionally in Fig. 1 as it comes from the preceding pass and is shown entering the final pass wherein the finger flange 2 is bent over or curved as best shown in Fig. 2. The web of the section is indicated by the numeral 1 and 3 indicates the "thumb" or "hook" flange which is finished and necessary to be protected from being deflected or bent in its passage through the guides and rolls.

A desirable arrangement of the guides is here shown and is adapted to permit of the assembling and adjusting of the guides to the pile at any convenient place thereafter to be alined with the rolls as a unit. The entry or guide box so formed comprises the side-guide members 12—12 spaced to receive between them the section to guide it, whereby it is delivered at a right angle to the rolls in correct relation to the pass, for this purpose being provided with guide-shoulders 14—14 on their inner sides to engage the outer surfaces of the pile-flanges or fingers 2 as shown. The opposed guide surfaces of the shoulders 14—14 are shown formed to provide a flared or bell-mouthed entry or guide-way; for this purpose the outer ends of the shoulders are curved at 15—15. A lower pass guide desirably is formed by the lower members 16—16 formed integrally with the side members 12 and recessed at 18—18 to receive the inner or hook flanges of the pile. This lower guide is desirably inclined as shown. The guide members are securely fastened together by horizontal bolts 20—20 and the correct spacing is accomplished by inserting a suitable liner or spacer 22 between the members as shown. From the engagement of the guide shoulders 14 with the longer pile flanges it results that the thinner and more flexible hook-flanges 3 are protected from coming into contact with any part until they enter the rolls and therefore are in no danger of being bent, as it will be seen that the recesses 18 are enlarged to leave a free space around the hooks. The necessity for so protecting the hooks is due to the fact that the hook flanges are the widest part of the section as it comes from the preceding pass and are therefore liable to be bent by contact with guides or

by the swaying from side to side of the section in passing through the rolls. The shoulders 14-14 are of such length and at such distance from the rolls to obtain the best results.

- 5 The inner faces of the side members 12 are recessed at 24 to receive the mandrel plates 26 having fixed thereon the mandrels 28. These mandrels I have found desirable 10 to employ to assist the final pass in the formation of the curved guards or flanges thereby to insure the uniform curvature of the flanges, this result being accomplished by the relative formation and adjustment of 15 the mandrels to the rolls whereby the flanges are bent over the mandrels as best shown in Figs. 1 and 2. Their inner portions are desirably inclined at 28° as shown. The correct positioning of the mandrels relative to 20 the rolls is permitted by the adjustment of the mandrel supporting plates 26 vertically within the recesses 24, provision for this adjustment being made by elongated apertures 25 in the side members to which are fitted securing bolts 30 threaded in the mandrel plate so that when tightened the bolts securely hold the mandrel in adjusted position. Further to add to the security of the mandrel I desirably provide a shoulder 32 30 on the end of the mandrel plate 26 to engage an opposed shoulder 33 on the side-member 12 thus positively insuring against the mandrel being pulled through the rolls even should the securing bolts loosen or be sheared. The engagement of the shoulders 32 and 33 in addition maintains the correct 35 horizontal position of the mandrels but without interfering with their vertical adjustment.
- 40 The mandrels shown coöperate with the guide-shoulders 14 with which they are substantially in vertical alinement whereby are provided long guiding bearings to the pass. In addition these mandrels serve a 45 double purpose, one being to keep the above mentioned hook flange 3 of the section from turning up while going through the rolls, and the other as described the important function of preventing the longer finger 50 flanges 2 of the section from closing in more than is desired to form a perfect section.
- An upper pass-guide 35 is secured and supported by a supporting plate 36 by being bolted thereto by means of the bolt 37. The 55 supporting plate 36 is secured by the securing bolts 38. The guides are all supported by the rest bar 40 arranged to extend across the rolls and parallel thereto. These side guides as heretofore explained are adjusted 60 and secured by the bolts 20 thus to form an entry guide box which is rigid and self contained thereby permitting it to be adjusted laterally on the rest bar as a unit then to be rigidly held in place by the bolts 38-38 65 passing through the side members. This

arrangement of the guides as a unit to form an entry box is important as it permits of its adjustment and removal as a whole without disturbing the positions of its individual parts and also permits of minute adjustments being made under the most favorable conditions of light, etc., it being understood that upon proper adjustment and relative positions the successful rolling depends to a large degree.

Having described my invention I claim,

1. An entry guide of the character described comprising oppositely arranged and separable guide members, side guide shoulders having tapered ends on said guide members, a lower pass guide formed by inward projections of the guide members, a spacer interposed between the guide members, means rigidly to couple the guide members as a guiding unit and means to secure the guiding unit so formed in position relative to the rolls.

2. An entry guide of the character described comprising oppositely arranged and relatively adjustable side guides, mandrel guides suitably supported to be adjustable with the side guides and arranged to be vertically adjustable with relation to the side guides, an engaging shoulder to maintain the horizontal position of the mandrel and to prevent its forward movement, means to couple the side guides to form a guiding unit and means adjustably to secure the guiding unit so formed in position relative to the rolls.

3. An entry guide of the character described comprising oppositely arranged and separable guide-members, side guide-shoulders having tapered ends integrally formed on said guide-members, a lower pass guide formed by integral inward projections of the guide members to engage the section web, said lower guide having recesses for the free passage of the section hook flanges, and inclined at its front portion, mandrel supporting plates fitted to recesses in the guide-members, elongated apertures in the guide-members, securing bolts threaded to the plates and fitted within the apertures to secure the plates, mandrels forwardly extended from said plates between the rolls, an engaging shoulder on the mandrel plate to engage the guide-member, coupling bolts to couple the guide-members, an upper pass guide plate supported on the guide members, an upper pass guide on said plate and means to secure the guides with relation to the rolls.

4. In an entry guide to be used with rolls for rolling metal bars, an integral bottom side guide arranged at a right angle, the side portion having an inwardly extending shoulder, an upward extension above the shoulder, and a recess on its inner surface rearwardly of the shoulder to receive a mandrel,

and the bottom portion having a recess on its upper surface beneath the shoulder to receive a flange on the bar.

5. In an entry guide to be used with rolls 5 for rolling metal sheet pile sections having on each edge a finger and a thumb, an integral guide member having a bottom element and a side element arranged at a right angle to each other, an inwardly extending shoulder 10 on the side element having an inclined surface to engage with the finger and a flared front end, said side element having a recess on its inner surface rearwardly of the shoulder and extending above the same to afford 15 a seat for a plate supporting a mandrel guide, and the lower element having a downwardly inclined upper surface with a downwardly curved front end to engage with the section web and a recess on its upper surface 20 below the shoulder freely to receive the thumb.

6. An entry guide of the character described comprising side guide members and mandrel guides adjustably supported on the 25 side members said side members and mandrels being formed with abutting shoulders to maintain the horizontal position of the mandrels and means for securing the mandrels to the side guide members substantially as described.

7. An entry guide of the character described comprising side guide members arranged to be separable for relative lateral adjustment, mandrel guides supported on 35 the side guides in fixed vertical alinement therewith to be laterally adjustable with the side guides and adapted independently to be adjusted with relation to the side guides with reference to the horizontal.

- 40 8. An entry guide of the character described comprising side guide members arranged to be separable for relative lateral adjustment, mandrel guides supported on the side guides in fixed vertical alinement therewith and to be laterally adjustable with the side guides and adapted independently to be adjusted with relation to the side guides with reference to the horizontal,

means rigidly to couple the guide members as a guiding unit and means to secure the 50 guiding unit so formed in position relative to the rolls.

9. An entry guide of the character described comprising side guide members arranged to be separable for relative lateral 55 adjustment, a lower pass guide formed by integral flanges of the side guides, mandrel guides supported on the side guides in fixed vertical alinement therewith to be laterally adjustable with the side guides and pass 60 guide flanges and said mandrel guides being adapted independently to be adjusted with relation to the side guides with reference to the vertical.

10. An entry guide arrangement of the 65 character described comprising separable side guide members, mandrels carried thereby, means to couple the side guide members as a unit, a top guide supporting plate, a top guide supported thereon, a supporting bar 70 for the guiding unit and clamping means operative to clamp the guiding unit onto the supporting bar and to secure the top guide supporting plate substantially as described.

11. An entry guide adapted for use with 75 rolls for rolling metal bars having hook flanges on their marginal edges comprising separable side guide members arranged to be relatively adjustable and having inwardly extending guide shoulders adapted to engage outwardly directed surfaces of the bar at a point within the marginal edges thereof, mandrel guides adjustably supported on the side members, said side members and mandrels being formed with abutting shoulders 80 to maintain the horizontal position of the mandrels and means rigidly to couple the guide members as a guiding unit, substantially as described.

In testimony whereof I have signed my 90 name to this specification in the presence of two subscribing witnesses.
